UNITED STATES PATENT OFFICE.

FRANK D. WARD, OF NEW YORK, N. Y.

CAR-BRAKE STRUT.

1,242,090.

Specification of Letters Patent.

Patented Oct. 2, 1917.

Application filed August 24, 1916. Serial No. 116,638.

To all whom it may concern:

Be it known that I, FRANK D. WARD, a citizen of the United States of America, and residing in the city, county, and State 5 of New York, have invented a certain new and Improved Car-Brake Strut, of which the following is a specification.

The present invention relates to struts and particularly to a strut for car brakes, the 10 object of my invention being to provide a strut of light yet rigid construction adapted to be connected between the brake levers and having means whereby the distance between the attaching centers on the strut may 15 be readily varied and also providing improved bearings between the parts.

Referring to the accompanying drawings, Figure 1 is a side elevation of a strut in which my invention is embodied in illustrative form;

Fig. 2 is a plan thereof, showing one of the brake levers in cross section;

Fig. 3 is a longitudinal section through the strut and lever ends on the line 3—3, 25 Fig. 2; and

Fig. 4 is an enlarged section through one of the lever ends and bearing.

The common practice heretofore in the construction of struts of the present type, 30 has been to use a strut having two end members united by a turn buckle arrangement for varying the overall length of the strut and thus the distance between the centers, one each at the opposite ends of the strut. 35 This construction is deficient not only by reason of the difficulty of operating the turn buckle after it has become rusty or clogged with ice, dirt, etc., and the consequent loss of time in the adjustment, but 40 also by reason of the fact that the eye in each end section, through which the bearing bolt is passed, becomes quickly worn with the result that rattling and chatter ensue, which render the attachment noisy as well 45 as giving a sense of insecurity. A certain amount of lost motion also results and this combined with the fact that the turn-buckle occasionally jars loose and causes an undesired lengthening of the distance between 50 centers, renders the strut highly objectionable from the standpoint of efficiency and workmanlike construction.

The present strut is free from the objections noted, while possessing several other 55 advantages thereover. As here shown it comprises a pair of bars 10 and 11 of equal

length, spaced apart in the mid-portion of their length by spacing thimbles 12 and 13 through which freely pass the securing means, such as rivets 14 or bolts 15, by 60 which the bars are rigidly united together. At one end of the strut, the bars 10 and 11 are pierced by a series of registering eyes 16 spaced longitudinally apart a predetermined distance, which may, for example, be two 65 inches, the major spacing unit. At the other end of the strut, the bars are similarly pierced by a second series of eyes 17, spaced a different distance apart—say one and a half inches, the minor spacing unit. Closely 70 fitting these eyes, so as to prevent rattling, are the pivot pins or bolts 18 and 19 by which the levers 20 and 21 respectively, of the brake system are connected to the strut.

The spacing of the eyes at each end of the 75 strut is predetermined by the desired distance between centers for the attachment to the brake levers. For example, the distance between the terminal eyes 16 and 17 at opposite ends of the strut may be twenty-seven 80 inches. Assuming that the eyes are spaced as stated, the distance between the eye 16 at the inner end of its series and say the second eye 17 from the inner end of its series, will be sixteen and one-half inches, and that 85 spacings from seventeen inches to twenty-four inches variations of length, differing by one-half inch, can be obtained (with the exception of seventeen and one-half), the possible distances above twenty-four inches 90 being twenty-five, twenty-five and one-half and twenty-seven inches. Thus with a link which measures twenty-seven inches between centers of the terminal eyes and is provided at one end with four eyes and at 95 the other end with five eyes as described, it is possible to secure nineteen different variations of spacing between centers for the connection to the brake levers.

To minimize wear on the strut eyes and 100 prevent rattling by the pivot pins, not only are the latter made to fit the eyes closely but they are also provided with snug steel bushings 22—23 of the same length as the thimbles 12, 13, and serving, like the latter, to 105 space apart the bars 10 and 11 which form the strut. Arranged thus between the ends of the bars and rigidly spacing them apart, they serve to prevent vibration at these points. Furthermore any wear that occurs 110 between the brake levers and the strut is taken by these bushings and they may be

readily renewed by simply withdrawing the pivot bolts and replacing the worn bushings when need arises.

Further to reduce wear on major parts and to keep the assembled parts snug, I provide the lever eyes with coöperating bushings 24, 25, which fit over the strut bushings 22, 23. These several bushings being of hard steel, the wear is slight and the parts remain snug and tight with no necessity for renewal for long periods of time.

The construction described is merely illustrative of my invention which is not limited to the two bar construction or various other features of detail particularly described in pointing out my invention.

I claim as my invention:—

1. The combination with a pair of supports, of an inextensible connecting strut having at one end a series of eyes spaced by a unit of distance and at the other end a series of eyes spaced by a different unit of distance, and pins connecting the opposite ends of the strut to said supports.
2. A strut comprising a pair of bars rigidly united in spaced relation at their mid-portion, and having a longitudinal series of registering transverse eyes at one end of said bars and at the other end of said bars a longitudinal series of registering transverse eyes differently spaced from those of the first series.
3. A strut comprising a pair of bars, hav-

ing at their opposite ends longitudinal series of eyes, spacing thimbles arranged between said bars at their mid-portion, means passing freely through said thimbles and piercing said bars and serving to unite the latter in permanent relationship, a pivot bolt at each end of said strut passing through registering eyes in the bar ends, and bearing bushings snugly fitting said bolts and spacing the bars apart at their ends.

4. A strut comprising a pair of bars, having at their opposite ends longitudinal series of eyes, spacing thimbles arranged between said bars at their mid-portion, means passing freely through said thimbles and piercing said bars and serving to unite the latter in permanent relationship, a pivot bolt at each end of said strut passing through registering eyes in the bar ends, and bearing bushings snugly fitting said bolts, in combination with a pair of supports extending between said bars and having eyes through which said pivot bolts pass, together with bearing bushings in said eyes of the supports, substantially as described.

In testimony whereof I have signed my name to this specification, in the presence of two subscribing witnesses.

FRANK D. WARD.
